UNITED STATES PATENT OFFICE

MAUNSELL B. JACKSON, OF TORONTO, ONTARIO, CANADA

STARTER FOR ENGINES

Application filed February 11, 1926. Serial No. 87,647.

This invention relates to starters for internal combustion engines of the type in which the starter pinion is manually moved into meshing engagement with the engine gear, and more particularly to the type of starter disclosed in my prior applications Serial Numbers 67,577, and 81,014, filed November 7, 1925 and January 13th, 1926, respectively, in which a continuous movement of the operating mechanism, for meshing the starter pinion with the engine gear, axially moved the pinion and rotated it as necessary to align it with the gear. The mechanisms in the above applications each included a single finger having one or more teeth, each tooth being adapted to axially move the pinion and rotate it as necessary to align it with the gear. The object of the present invention is to provide separate means for axially moving the pinion and for rotating it, if necessary, to mesh it with the gear under all conditions.

I attain my object by providing a resilient finger normally held out of action by manually controlled means, the finger tending to axially move the pinion towards the engine gear; and by providing a second finger, directly operated by the manually controlled means, for rotating the pinion if its teeth meet end to end with the teeth in the gear, the first finger being adapted to move the pinion axially again when the second finger has rotated it sufficiently to align its teeth with the spaces between the gear teeth. The constructions are hereinafter more fully described and illustrated in the accompanying drawings in which

Fig. 1 is a side elevation, partly in section, of my starter showing the parts in their inoperative positions;

Fig. 2 a sectional detail, partly in side elevation, showing the position of the parts when the pinion teeth have met the gear teeth end to end and the finger for rotating the pinion is in its initial position of engagement with the latter;

Fig. 3 a plan view, partly in section, of the shaft and pinion parts shown in Fig. 2;

Fig. 4 a view similar to Fig. 2 showing the position of the parts when the pinion has

been rotated to align its teeth with the spaces between the gear teeth; and

Fig. 5 a detail in end elevation of the pinion actuating arms.

1 is an electric motor provided with an extended armature shaft 2 having its outer end turned down to receive the sleeves 3^a and 3^b. The sleeve 3^a is keyed on the shaft and is provided with notches to receive projections 3^c formed on the sleeve 3^b. The sleeves are held, by a collar 3^d, from axial movement and the sleeve 3^b has long pitched threads 3 formed thereon. A pinion 4 threaded on the threads 3 is adapted to be manually moved, both axially and rotarily, into mesh with a gear 5 connected with the crankshaft of an engine (not shown), the common practice being to secure this gear to the engine flywheel.

A bell crank 6 is journaled on a spindle 7 which is suitably mounted on the starter pinion housing 1^a. An arm 6^b of the bell crank is connected with any suitable manually operated mechanism such as the foot pedal or plunger 8 shown in Fig. 1. On the other arm 6^a of the bell crank is pivoted a finger 20 which is provided with a flat end 21 adapted to be engaged by a flat spring 22 carried by the arm 6^a. The finger is adapted to engage a serrated peripheral flange 4^a formed on a disk 4^b suitably carried on the end of the pinion. The spring 22 tends to retain the finger in its normal position. A spring 19 is adapted to normally maintain the foot plunger 8 and thus the bell crank 6 and finger 20 in their inoperative positions as shown in Fig. 1. It will be noted that the finger is normally spaced from the serrations 4^a.

An arm 23, located between the arm 6^a and the sleeve 3^a, is also journaled on the spindle 7. On the arm 23 is pivoted a finger 24 which is provided with a flat end adapted to be engaged by a flat spring 25 carried by the arm 23. This finger is adapted to engage the disk 4^b to axially move the pinion towards the gear 5. A coil spring 26 disposed on the hubs of the bell crank 6 and the arm 23 has its ends extending laterally in opposite directions. The end 27 of the spring engages the arm 6^a and the end 28 engages the arm 23 to

tend to swing the arms towards one another and this movement is limited by means of a pin 29 carried by the arm 23 and adapted to engage the arm 6^a. These parts are held, by means of a screw 30 threaded in the end of the spindle, from lateral displacement.

From this description it is obvious that by depressing the foot device 8, the arm 6^a will be rocked towards the pinion and away from the pin 29. This will permit the coil spring 26 to partially rotate the arm 23 and thus its finger 24 to axially move the pinion towards the gear 5 and into meshing engagement therewith if the pinion teeth are in alignment with the spaces between the engine gear teeth when the pinion and gear come together.

If the teeth of the pinion and gear meet end to end when the pinion is being axially moved, by the finger 24, towards its meshing position, the axial movement of the pinion towards the gear will be stopped which will result in the movement of the finger 24 being temporarily checked. The arm 6^a is then drawn farther away from the pin 29 to engage the finger 20 with the serrations 4^a and this will result in the finger 20 rotating the pinion sufficiently to cause its teeth to clear the teeth of the gear. This is due to the finger 20 swinging in a plane located at one side of the axis of the pinion and being at an angle to the said axis. When the finger 20 has rotated the pinion teeth past the contacting gear teeth, the spring 26, which has been tensioned by the movement of the arm 6^a relative to the arm 23, actuates the arm 23 and thus the finger 24 to again move the pinion axially of the shaft and into meshing engagement with the gear teeth. In other words the finger 24 axially moves the pinion and, if necessary, the finger 20 rotates it until it is in position for meshing with the gear and then the finger 24 again axially moves the pinion into mesh with the gear.

A spring pressed plunger 11 of an ordinary plunger type switch, connected in the motor circuit, is adapted to be engaged by the arm 6^b of the bell crank 6 to energize the motor when the pinion teeth are in meshing engagement with the gear teeth. The shaft 2 is thus rotated to thread the pinion, which is held from rotation by the gear, along the shaft and fully into mesh with the gear. When the pinion engages the collar 3^d, its axial movement is stopped and it rotates with the shaft to drive the gear.

The pinion is automatically returned to its inoperative position, when the engine is started, in the usual manner. If the motor switch is closed when the engine starts, the pinion when moving from its operative or meshed position to its inoperative position will engage the fingers 20 and 24 and swing them on their pivots against the compression of the flat springs 22 and 25. This arrange-

ment permits the fingers to be partly folded up, by means of the frictional contact between them and the pinion, to prevent them from being damaged. Should the engine back fire and thus rotate the pinion in a reverse direction the springs 22 and 25 are adapted to permit the fingers to be rocked in the direction of rotation of the pinion.

Referring to Figs. 1 and 4 it will be seen that the spring 22 is also adapted to permit the finger 20 to be partly folded up during its operative movement if it is necessary to rotate the pinion through a large arc to move its teeth clear of the gear teeth. As the coil spring 26 is forcing the finger 24 against the disk 4^b while the pinion is being rotated, the finger 24 is also partly folded up against its spring 25.

It will be understood that various modifications of the parts may be devised without departing from the spirit of my invention.

What I claim is:

1. An engine starter drive including a rotatable shaft; a starter pinion mounted thereon for rotary movement therewith and for longitudinal movement thereof to mesh with a gear of the engine to be started; and manually operable means including two fingers, one finger being adapted to cause such longitudinal movement of the starter pinion, the other finger being adapted to cause a rotary movement of the pinion during its longitudinal movement towards the meshing position if the teeth on the latter meet end to end with the teeth on the gear.

2. In a starter for use with an internal combustion engine having a gear adapted to rotate the crankshaft thereof, the combination of starter mechanism including a shaft; a starter pinion threaded on the shaft; and manually operable means including two fingers, one finger being adapted to axially move the pinion into meshing engagement with the gear, the other finger being adapted to rotate the pinion if the teeth on the latter meet end to end with the teeth on the gear, the first mentioned finger being adapted to again axially move the pinion when its teeth clear the gear teeth.

3. An engine starter drive including a rotatable shaft; a starter pinion mounted thereon for rotary movement therewith and for longitudinal movement thereof to mesh with a gear of the engine to be started; manually operable means including a finger normally disengaged from the pinion and adapted to engage it eccentric to its axis; a second finger; and resilient means tending to actuate the second finger to cause such longitudinal movement of the pinion, the second finger being controlled by the first mentioned finger.

4. An engine starter drive including a rotatable shaft; a starter pinion mounted thereon for rotary movement therewith and

- for longitudinal movement thereof to mesh with a gear of the engine to be started; manually operable means including a finger normally disengaged from the pinion and adapted to engage it eccentric to its axis; a second finger adapted to engage the pinion; a coil spring tending to move the fingers towards one another and tending to actuate the second finger to cause such longitudinal movement of the pinion; and stop means for limiting the said movement of the fingers towards one another. 5 70
5. An engine starter drive including a rotatable shaft; a starter pinion mounted thereon for rotary movement therewith and for longitudinal movement thereof to mesh with a gear of the engine to be started; a pivoted finger normally disengaged from the pinion and adapted to engage it eccentric to its axis; a second finger adapted to cause such longitudinal movement of the starter pinion; resilient means tending to actuate one of the said fingers; and manually operable means adapted to control the finger operated by the resilient means and to directly actuate the other finger. 15 75
6. An engine starter drive including a rotatable shaft; a starter pinion mounted thereon for rotary movement therewith and for longitudinal movement thereof to mesh with a gear of the engine to be started; a spindle; an arm journalled on the spindle and provided with a finger normally disengaged from the pinion and adapted to engage it eccentric to its axis; a second arm journalled on the spindle and provided with a finger adapted to engage the starter pinion; resilient means tending to actuate the second mentioned arm to cause such longitudinal movement of the pinion; and manually operable means adapted to actuate the first mentioned arm and adapted to control the second mentioned arm to permit such longitudinal movement of the starter pinion. 20 80
7. An engine starter drive including a rotatable shaft; a starter pinion mounted thereon for rotary movement therewith and for longitudinal movement thereof to mesh with a gear of the engine to be started; a spindle; an arm journalled on the spindle and provided with a finger normally disengaged from the pinion and adapted to engage it eccentric to its axis; a second arm journalled on the spindle and provided with a finger adapted to engage the starter pinion; resilient means tending to actuate the second mentioned arm to cause such longitudinal movement of the pinion; and manually operable means adapted to actuate the first mentioned arm and adapted to control the second mentioned arm to permit such longitudinal movement of the starter pinion. 25 85
8. An engine starter drive including a rotatable shaft; a starter pinion mounted thereon for rotary movement therewith and for longitudinal movement thereof to mesh with a gear of the engine to be started; a spindle; an arm journalled on the spindle and provided with a finger normally disengaged from the pinion and adapted to engage it eccentric to its axis; a second arm journalled on the spindle and provided with a finger adapted to engage the starter pinion; resilient means tending to actuate the second mentioned arm to cause such longitudinal movement of the pinion; and manually operable means adapted to actuate the first mentioned arm and adapted to control the second mentioned arm to permit such longitudinal movement of the starter pinion. 30 90
9. An engine starter drive including a rotatable shaft; a starter pinion mounted thereon for rotary movement therewith and for longitudinal movement thereof to mesh with a gear of the engine to be started; manually operable means including two arms, each arm having a finger pivoted thereon, each finger having a flat end; and flat springs carried by the arms for engagement with the said flat ends to tend to retain the fingers in their normal positions, one finger being adapted to cause such longitudinal movement of the starter pinion, the other finger being adapted to cause a rotary movement of the pinion during its longitudinal movement towards the meshing position if the teeth on the latter meet end to end with the teeth on the gear. 35 95
10. An engine starter drive including a rotatable shaft; a starter pinion threaded thereon for rotary movement therewith and for longitudinal movement thereof to mesh with a gear of the engine to be started; means normally inoperative adapted to rotate the pinion; and separate means controlled by the first mentioned means for causing such longitudinal movement of the starter pinion, the first mentioned means being adapted to rotate the pinion should the latter collide with the gear, the first and second mentioned means having provisions to admit both an overrunning rotation and a return axial movement of the pinion before the first mentioned means is returned to its normally inoperative position, whereby the pinion may be automatically de-meshed by the thread. 40 100
11. In a starter drive for internal combustion engines, a starter shaft; a pinion threaded on the shaft for longitudinal movement thereof and rotary movement therewith; a gear of an engine to be started; a 45 105

device adapted to yieldingly press the pinion against the gear of the engine without imparting turning movement to the pinion; a second device adapted to press the pinion against the engine gear and at the same time to turn the pinion to bring its teeth into meshing relationship with the teeth of the engine gear; and a manually operable part adapted to actuate the first mentioned device and subsequently actuate the second device should the pinion and gear teeth meet end to end, the said devices having provisions adapted to permit the pinion to eject automatically when the engine starts under its own power and before the said manually operable part is returned to its normal position.

12. An engine starter drive including a rotatable shaft; a starter pinion mounted thereon for rotary movement therewith and for longitudinal movement thereof to mesh with a gear of the engine to be started; a device adapted to impart such longitudinal movement to the starter pinion; a second device adapted to turn the pinion should it collide with the gear; means for resiliently transmitting the movement of one device to the other; and manually operable means for actuating one of the devices and thus causing the resilient means to actuate the other device.

Signed at Toronto, Canada, this 27th day of January, 1926.
